UNITED STATES PATENT OFFICE.

ALBIN H. LARSON, OF MINNEAPOLIS, MINNESOTA.

RESILIENT PLATFORM FOR STREET-CARS.

1,122,956.

Specification of Letters Patent. Patented Dec. 29, 1914.

Application filed September 28, 1914. Serial No. 863,903.

To all whom it may concern:

Be it known that I, ALBIN H. LARSON, a citizen of the United States, residing at Minneapolis, in the county of Hennepin and State of Minnesota, have invented certain new and useful Improvements in Resilient Platforms for Street-Cars; and I do declare the following to be a full, clear, and exact description of the invention, such as will enable others skilled in the art to which it appertains to make and use the same.

My invention relates to improvements in street car platforms and more particularly to a supplemental spring supported platform designed to be positioned upon the ordinary platform of a car, whereby the motorman, standing upon said supplemental platform, will not be unnecessarily jarred and shaken.

In carrying out the above end, a further object of the invention becomes to provide simple means whereby the supplemental platform may be adjusted vertically to allow for more or less downward yielding movement.

A still further object is to provide for the attachment of additional springs, to be employed in case the device is to be used by a rather corpulent motorman.

Yet another object is to construct the entire device in an extremely simple manner for performing the functions for which it is designed.

With the above and minor objects in view, the invention resides in certain novel features of construction and combination herein described and claimed and shown in the drawings wherein:

Figure 1 is a longitudinal section through a portion of a car platform, showing the application of the invention thereto; Fig. 2 is a transverse section through the platform showing a rear side view of the device; Fig. 3 is a horizontal section through parts rising from the platform and illustrating a top plan view of the invention. Fig. 4 is a detail vertical section as seen on the line 4—4 of Fig. 3, showing the application of an additional spring; and Fig. 5 is a detail horizontal section as seen on the line 5—5 of Fig. 2.

In the accompanying drawings, I have shown a portion of a car which includes one or more motormen's platforms P, the usual controlling box B, brake operating shaft S, dog D, and bell operating pin p. Designed to rest upon the platform P is a rectangular

bed frame 1 which comprises parallel longitudinal bars 2 and transverse end bars 3, the latter being preferably riveted to the bars 2, although they could well be formed integrally therewith. Rising from each end bar 3 is an upright standard 4 here shown as formed of a pair of angle iron bars 5 having two of their flanges in contact, the lower ends of said flanges being turned outwardly to provide attaching feet 6 through which bolts or rivets 7 pass, whereby the standards are rigidly secured in position upon the bed frame. It will be noted that the remaining flanges of the bars 5 depend a slight distance below the end bars 3 and contact with the inner edges thereof, this construction being provided in order to more rigidly brace the standards 4.

Contacting with the inner angular sides of the angle iron bars 5, are other angle iron bars 8, the flanges of which, contacting with the transverse flanges of the bars 5, are bent inwardly as seen at 9 to provide means for attaching the upper ends of coiled springs 10, said ends 9 being preferably provided with openings for this purpose. Passing through alined openings in the longitudinally extending flanges 8' of the angle iron bars 8, and through an upright slot 11 in the longitudinal flanges of the standard 4, is a clamping bolt 12, by means of which the bars 8 may be adjusted vertically in respect to the base or bed frame 1.

The lower ends of the springs 10 are here shown in the form of hooks 13 which pass through openings in the four corners of a rectangular platform plate or bar 14, said bar being thereby resiliently supported, and being designed to receive the heels of a motorman standing upon the device, the toes of the motorman being designed to be supported by a longitudinal board 16 which is hinged to the front edge of the frame 1 and which, in turn, is provided with a forwardly projecting extension 17 which is hinged to its forward edge, the extension 17 being located adjacent the dog D, whereby the motorman's right foot may be properly supported for actuating said dog. The board 16 is provided with an opening O through which the plunger p rises.

As most clearly seen in Fig. 4, the upper ends 9 of the bars 8, are spaced, this space being utilized, at times, for the reception of a shouldered eye-bolt 18 whose shank projects through said slot, a nut 19 being

threaded upon the upper end of said eye-bolt and contacting with the said ends 9. These eye-bolts 18 are provided in order that additional coiled springs 10' may be 5 provided, the lower ends of said springs being formed into hooks 13' which are passed through suitable openings in the transverse center of the plate 14, at its opposite ends. These additional springs 10', are only employed when a comparatively heavy motorman 10 is to use the device, the addition of other springs being then essential in order to properly support the added weight.

From the foregoing description, taken in 15 connection with the accompanying drawings, it will be seen that I have produced extremely simple construction for carrying out the objects of the invention, yet that this structure will well perform the functions 20 for which it is designed and will possess numerous advantageous features, the most prominent of these features being the fact that the device absolutely prevents shocks and jars from being imparted to the 25 feet and legs of the motorman.

I have described my invention with considerable minuteness and have set forth certain specific forms for carrying out the 30 objects of the invention but it is to be understood that I need not be limited to details of construction other than those set forth in the appended claims.

I claim:

1. A base, a pair of spaced vertically adjustable standards rising therefrom, coiled springs depending from said standards, and a platform supported by said springs.

2. A base, angle iron standards rising therefrom, angle iron bars fitting slidably 40 within the angles of said angle iron standards and having spring supporting ears, adjusting bolts passing through said angle iron

standards and the bars, springs depending from said spring supporting ears, and a platform supported by said springs.

45

3. A rectangular bed frame including longitudinal side bars and transverse end bars, angle iron standards rising from said end bars and each having a longitudinally extending flange and a transversely extending flange, the lower ends of the longitudinal flanges being bent laterally to provide attaching feet, fasteners passing through said attaching feet and through said end bars, angle iron bars fitting slidably within the 50 angles of said angle iron standards coiled springs depending from said angle iron bars, a platform supported by said coiled springs, and means whereby said angle iron bars may be adjusted vertically in respect to said angle 55 iron standards.

4. A resiliently supported supplemental platform designed to be positioned upon a car platform, said supplemental platform being designed to receive the heels of a motorman, a board in advance of the supplemental platform and designed to receive the toes of the motorman, and an extension on the forward edge of said board for the 60 purpose set forth.

70

5. A resiliently supported supplemental platform designed to be positioned upon a car platform and to receive the heels of a motorman, and a board in advance of the supplemental platform and designed to receive the toes of the motorman.

75

In testimony whereof I have hereunto set my hand in presence of two subscribing witnesses.

ALBIN H. LARSON.
